[57] CLAIM

The ornamental design for a hanger, as shown and described.

DESCRIPTION

FIG. 1 is a front elevational view of the hanger showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof in a first position of use; and,

FIG. 8 is a perspective view thereof in a second position of use.

In FIGS. 7 and 8, the broken line showing of an article of clothing is for illustrative purposes only and forms no part of the claimed design;
